UNITED STATES PATENT OFFICE.

HERMAN IHLENBURG, OF PHILADELPHIA, PENNSYLVANIA, ASSIGNOR TO THE MACKELLAR, SMITHS & JORDAN COMPANY, OF SAME PLACE.

DESIGN FOR A FONT OF TYPE ORNAMENTS.

SPECIFICATION forming part of Design No. 17,341, dated May 10, 1887.

Application filed April 8, 1887. Serial No. 234,188. Term of patent 7 years.

To all whom it may concern:

Be it known that I, HERMAN IHLENBURG, (assignor to THE MACKELLAR, SMITHS & JORDAN COMPANY,) of the city and county of Philadelphia, Pennsylvania, have invented and produced a new and original Design for a Font of Type Ornaments, representing scroll, foliate, and figured ornamentation for borders and ornamental surroundings for printed matter, of which the following is a specification.

The nature of my design is clearly shown in the accompanying typographic impression, to which reference is made, and in which the various types (numbered from 1 to 68, inclusive) are shown, as well as an example to show how these various types may be combined to form an entirety.

Nos. 1 to 15 represent the sections or types employed in connection with the sections or types numbered from 17 to 40 and from 42 to 20 52, and 54, 55, 56, 57, and 58, to form a border proper, while Nos. 16, 41, 53 and the sections or types from 59 to 68, inclusive, are employed for the interior ornamentation of the same, either as shown in the entirety or any other 25 ornamentation they may be combined to form.

Having now described my invention, I claim as new—

The design, as shown and described, for a font of type ornaments, consisting of a series 30 of types numbered from 1 to 68, inclusive, and representing scroll, foliate, and figured ornaments, as set forth.

HERMAN IHLENBURG.

In presence of—

C. F. HUCH,
HERMAN METIUS.
